UNITED STATES PATENT OFFICE.

HARRY L. KING, OF SPOKANE, WASHINGTON.

DESIGN FOR A SPECTACLE-TEMPLE TIP.

SPECIFICATION forming part of Design No. 32,274, dated February 27, 1900.

Application filed February 1, 1900. Serial No. 3,649. Term of patent 7 years.

To all whom it may concern:

Be it known that I, HARRY L. KING, a citizen of the United States, residing at Spokane, in the county of Spokane and State of Washington, have invented a new and useful Design for Spectacle-Temple Tips, of which the following is a specification.

My invention relates to a design for spectacle-temple tips, which is illustrated in the accompanying drawings.

Figure 1 is a perspective view of a temple-tip embodying my design. Fig. 2 is a side elevation of the same. Fig. 3 is a cross-sectional view thereof.

My design of a spectacle-temple tip consists of an elongated body portion A, which is concaved or curved, as shown, the inner edge a

being tapered or wedge shape, constituting an elongated tapered inner edge to the tip, and the tip in cross-section being approximately 20 triangular, as illustrated in Fig. 3.

Having thus described my invention, what I claim, and desire to secure by Letters Patent, is—

The design for a spectacle-temple tip substantially as herein shown and described.

In testimony whereof I have hereunto set my hand in the presence of two subscribing witnesses.

HARRY L. KING.
